UNITED STATES PATENT OFFICE.

HALBERT K. HITCHCOCK, OF PITTSBURGH, PENNSYLVANIA, ASSIGNOR TO PITTSBURGH PLATE GLASS COMPANY, A CORPORATION OF PENNSYLVANIA.

APPARATUS FOR SURFACING SHEETS OR PLATES.

Application filed June 1, 1922. Serial No. 565,052.

The invention relates to apparatus for surfacing glass sheets or plates of glass or other material, i. e. grinding or polishing the surface of the sheets or both, and, as applied to glass sheets, is designed particularly for work upon the smaller sizes. The apparatus is illustrated as applied to the surfacing of square sheets, but it will be understood that it is designed for use upon, and may be used to the same advantage with, sheets of a wide variety of shapes and proportions.

One object of the invention is the provision of an apparatus which requires no setting of the sheets upon supporting tables by the use of plaster or other means as is now commonly done. A further object is the provision of an apparatus in which the work of grinding and polishing may be carried out in a continuous operation. A still further object is the provision of an apparatus of the character stated which is in a large degree automatic, requiring only a minimum amount of hand labor and attention. The foregoing and other objects are secured by the apparatus as hereinafter described and illustrated in the accompanying drawings wherein:

Figure 1 is a plan view of the apparatus; Fig. 2 is a partial section and partial side elevation; Figs. 2^a, 2^b and 2^c are detail views showing the means for adjusting the drive shafts of the tables; Fig. 3 is an end elevation of the apparatus at the left-hand end of Fig. 1; Fig. 4 is an end elevation at the right-hand end of Fig. 1; Fig. 5 is a diagrammatic plan view of one of the tables illustrating the sand distribution; Fig. 6 is a section through the construction of Fig. 5; Fig. 7 is a vertical section on the line VII—VII of Fig. 8; Fig. 8 is a partial side elevation and partial section on the line VIII—VIII of Fig. 7; Fig. 8^a is a section on the line VIII^a—VIII^a of Fig. 7; Fig. 9 is a partial top view and partial bottom view of the suction device employed for supporting the sheets to be surfaced, the upper left-hand quarter of the view showing the bottom of one of the sucker devices; Fig. 10 is a partial side elevation and partial vertical section of the suction device of Fig. 9; Figs. 11, 12 and 13 are detail views showing the method of mounting the suction devices, Fig. 11 being an end elevation, Fig. 12 a side elevation and Fig. 13 a bottom plan view; Fig. 14 is a sectional view showing a modification of the

method of supporting the suction devices which method is preferred; Fig. 15 is a partial plan view of one form of table with all but a small section of one of the runner bars removed; Fig. 16 is an enlarged section on the line XVI—XVI of Fig. 15; Fig. 17 is a plan view of one of the runner bars; Fig. 18 is a side elevation, partially in section, of the runner bar of Fig. 17; Fig. 19 is a plan view of a modified table construction; Fig. 20 is a transverse section through the construction of Fig. 19; Fig. 21 is a plan view of one of the polishing tables; Fig. 22 is a transverse section through the construction of Fig. 21; Fig. 23 is an enlarged detail section through a small section of the polishing table; Fig. 24 is a partial plan view of another form of grinding table construction; Fig. 25 is a partial side elevation of and partial section through the construction of Fig. 24; and Figs. 26 and 27 are plan and side elevation views, respectively, of one of the runner bars of the Fig. 24 construction.

Briefly stated the apparatus, in the preferred form, comprises a series of rubbing beds in the form of relatively large rotating tables whose upper faces are provided with suitable grinding and polishing means, in combination with an endless carrier provided with a large number of plate or sheet supporting elements to which the sheets are releasably secured and which carries the sheets over the series of rubbing beds in paths such that a uniform wear, (as nearly as is possible) is secured upon the surfaces of the tables or beds. During this period of movement, the plates are (1) rough ground, (2) ground more and more finely by the use of finer and finer abrasive, and (3) finally polished, after which the plates are turned upside down with respect to the supporting elements, and the surfacing operation repeated upon the other sides thus presented to the rubbing beds. The number of tables or beds required will vary, depending upon the size of the tables and upon the flatness of the glass plates to be surfaced and the character of the surfaces thereof. It might be possible in some cases to complete the grinding operation on a single large table. The abrasive which is preferably used is sand, which is applied in a plurality of grades upon a single table or bed, the grade first used being the coarsest, with finer and finer grades progressively following as the plate

is gradually ground and its surface becomes smoother.

The devices for supporting the plates are preferably vacuum members which are automatically engaged with the plates at the beginning of the cycle and automatically released at the end. These devices may be actuated (pressed down on the glass plates) several times during the cycle to insure their continued holding action upon the plates, and are guided by an overhead track so as to secure a spiral path of movement of the plates as they move circumferentially around the tables, which arrangement serves to distribute the work of grinding over the entire surface of the tables.

Referring first to the general arrangement as shown in Figs. 1 to 4, the principal parts of the apparatus may be enumerated as follows:

A, B, C, and D are annular driven grinding tables or rubbing beds having their upper surfaces provided with grinding or surfacing means; E, F, G and H are polishing tables similar to the grinding tables, but having their upper faces provided with a polishing medium, such as felt or pitch; I, I, etc. are a series of plates to be surfaced, such plates being in the present instance sheets of plate glass supported by suitable carrying devices which releasably grip the upper surfaces of the plates; J is an overhead carrying track upon which the carrying devices are mounted, such track extending, as indicated in Fig. 1, circumferentially around each of the tables and from one table to the next, so that the plates may be carried successively over all eight of the tables; K is a conveyor at the left-hand end of the apparatus for carrying the plates beneath the belt device L, which serves automatically to secure the plate supporting devices to the plates preliminary to their passage over the first grinding table A; M is a receiving conveyor also located at the left-hand end of the apparatus for receiving the finished plates after they have been released from the carrying devices by means of the belt releasing device N; O, P, Q and R are a series of sprockets over which the endless carrying belts for the sheet carrying devices pass in the movement from one end of the cycle starting with the conveyor K and finishing with the conveyor M; S is the motor by means of which the endless carrier device is driven; T (Fig. 2) is one of the motors for driving the grinding and polishing tables, each table being driven independently by its own motor; U is the sand grader which is employed for grading the sand which is applied to the first three tables A, B and C; and V is a platform, shown in Fig. 1 as partially broken away, which is located between the grinders and polishers below the driving mechanism for

the endless carrier and serving to give convenient access to such mechanism.

The method of supporting and driving the grinding and polishing tables is shown in Fig. 2. As here shown, the table is driven from beneath, the driving mechanism being located in the chamber 1 which is preferably lined with concrete. The weight of the table is supported upon a head 1^a carried by the spindle 2 arranged so that when the spindle is lowered the weight of the table is transferred to the track 1^b, and the head then disconnected from the table. The spindle 2 is supported in the cylindrical base member 3 at its lower end and adjustable vertically by means of the wedge 4 interposed between the top of the member 3 and flange of the plunger 5. The thrust of the spindle 2 is taken by the bearing plates 1^c (Fig. 2^a). The wedge 4 is tapered as indicated in Fig. 2^b and held in adjusted position by the screw 1^d, and the plunger 5 is raised and lowered by the application of hydraulic pressure in the cylinder 3. This adjustment of the table is desirable in order to maintain the grinding surface of the table at the same level as such surface is worn down in service. The shaft of the motor drives the bevel gear 6 in the manner indicated and such gear 6 is mounted upon a short vertical shaft which has at its upper end a pinion (not shown), meshing with the spur gear 7, which is keyed to the spindle 2. The usual trough 8 (Fig. 2) is provided beneath the edge of each table to receive the mixture of water and abrasive which runs from the table, and in the case of the three grinders A, B and C, this mixture is conducted back to a sump or pit lying beneath the grader U (Fig. 1) and from which the grader is supplied by means of a suitable pump.

The grader itself is preferably of the type shown in the Bechtel Patent No. 1,089,894, issued March 10th, 1914, such tank being modified, however, to supply abrasive simultaneously to the three tables A, B and C instead of to two, as shown in the patent, and being arranged to supply several grades of abrasive to each table at the same time. This modification means only the addition of more outlet pipes than illustrated in the Bechtel patent, the method of operation being precisely the same, the abrasive and water running from the tables being collected and returned to the sump beneath the grader, after which it is regraded and circulated in a continuous cycle. The pipes for conducting the abrasive to the table A are shown in Fig. 5, there being four of these pipes 9, 10, 11 and 12 in this particular instance, although the number may be increased or decreased to suit requirements. The vertical portions of the pipes (Fig. 6) are secured to a supporting mast 13 sus-

pended from above with the lower ends extended diagonally and braced by means of the spider 14 carried upon the lower end of the mast. The pipe 9 supplies the coarsest abrasive, the abrasive supplied through the pipes 10, 11 and 12 being of increasing fineness. The table A has its central portion cut out, as indicated at 15, so as to provide the annular grinding bed, and in order to assist in getting the coarse abrasive from the first pipe 9 between the plates to be ground and the surface of the bed, the lower end of the pipe 9 is recurved, as indicated at 16 in Fig. 6 and supplies the water and abrasive upwardly across the bevel 17 at the inner edge of the table. The other pipes 10, 11 and 12 are extended over the table and supply the abrasive downwardly as indicated at 18 in Fig. 6, the discharge in each case occurring closely adjacent the plates on the table.

The plates of glass I to be ground in their passage to the table, over it, and away from it, follow the path of the track J heretofore referred to in the general description. The plates are lowered so that their faces engage the surface of the table when they reach the point *a*, at which point the coarse sand is applied. This sand is utilized in doing the roughest grinding until the plate arrives at the point *b*, at which point the next finer grade of abrasive is applied. The third grade of abrasive is applied at the point *c* and the last grade at the point *d*. It will be observed that the grinding starts when the plates are at the station *a* next to the inner periphery of the annular table and that, as the grinding progresses, the plates are carried gradually outward until they reach the periphery of the table at *e*, where the plate is lifted out of contact with the table. The path pursued is substantially spiral carrying the plates over the entire grinding surface of the table, which arrangement accomplishes the function of equalizing the wear over the grinding area of the table, so that its surface is reduced uniformly and thus kept flat. The rotation of the table causes the abrasive to work outward to the outer edge, so that very little of the coarse sand supplied at one station is carried around to the point of application of the next finer grade at the next station. In order to prevent the coarser sand from the station *c* from reaching the station *d*, the scraping device or baffle 20 is preferably employed between the two stations, such baffle having its lower edge provided with a sheet of rubber or other flexible material in contact with the surface of the rubbing bed. Another similar scraper 21 is provided intermediate the station *d* and the inner periphery of the table in order to direct the fine sand outwardly and prevent such sand from remaining upon the

table until station *a* is reached, as such fine sand tends to interfere with the action of the coarser abrasive supplied at the station *a*.

Although the system herein illustrated and described discloses three grinding tables A, B and C for use in connection with the grinding with sand, it may be possible to entirely smooth the surface of the glass upon a single table by making such table of sufficient size and providing a sufficient number of different grades of sand. In their movement around the table, the plates of glass are free and rotate about their vertical axes, by reason of the construction hereinafter more fully set forth, and the mounting is also made flexible, so that the glass can adjust itself to the surface of the table. These features facilitate the grinding of the plates and avoid the application of any undue strain to the plates tending to break them, such as would be the case if they were rigidly mounted and not free to rotate.

The grinding surfaces of the tables may be variously constructed as hereinafter set forth, the form illustrated in Fig. 5 involving the use of cast iron runner blocks 22 having their faces grooved in the curved form indicated at 22^a in this figure and also in Fig. 19. The runner bars are bolted to a suitable supporting framework 22' (Fig. 6). The grooves employed tend to direct the sand circumferentially and prevent it from being fed too rapidly across and off of the table, it being desirable that the sand as supplied at each station should be carried around and utilized until the plates reach the next station.

The overhead track J and the devices for supporting the plates I and carrying them along the track are shown in detail in Fig. 9 to 13. The track J is made up of the two sets of angle irons 23-23 and 24-24, shown in Figs. 11 and 12 and between these angles are the series of spindles 25 mounted for vertical movement and each provided at its lower end with a vacuum frame 26, shown in detail in Figs. 9 and 10. Each spindle 25 is mounted for rotation in a casing 27 and such casing is provided with short lateral bearing shafts 28 upon which are mounted the wheels 29 arranged as indicated in Fig. 11. The spindle casings 27 also carry the lateral brackets 30, shown in Fig. 12 upon which are mounted the vertical pins 31 carrying the rollers 32 which engage the inner vertical flanges of the track angles 23 and 24.

The spindle 25 is flexibly secured at its lower end to the vacuum frame 26, as indicated in Figs. 9 and 10. The lower end of the spindle is tapered and fits into a block 33, in which it is secured by means of the pin 37. This block is provided with three

arms 34 secured to the flexible coupling plate 35 by means of the bolts 38. This plate is preferably of spring steel or woven fabric impregnated with rubber and is secured at its outer edge to the vacuum frame by means of the bolts 36. This method of supporting the vacuum frame permits the sheet of glass to adjust itself to the surface of the table as heretofore specified and tends to prevent breakage.

The vacuum frame 26 is preferably made of cast iron and is provided with four sucker devices located at the corners of the frame. The frame at this point is made in skeleton form illustrated, with a collar 39 at the juncture of the radial arms 40. Each sucker device is made up of the two plates of rubber 41 and 42, the plate 42 being the glass engaging member and the plate 41 the member for producing the suction effect. The plate 41 has embedded in it the metal plate 43 carrying the headed pin 44 normally held in upper position by means of the spring 45. The lower end of this pin is provided with a rubber tip 46, which serves to engage the glass and disengage it from the sucker, as hereinafter set forth, when the pin 44 is pressed downwardly to a sufficient extent. The lower plate 42 has a skeleton framework 47 of metal, around which the rubber is molded, and this skeleton member, and the edge of the plate 41, are secured to the vacuum frame 26 by means of the series of bolts 48. The lower face of the plate 42 is preferably provided with grooves 49, as shown in Fig. 9. The space 50 between the plates 41 and 42 constitutes the vacuum chamber which is reduced in volume when the plate 42 is pressed down.

The spindle casing 27, shown in Figs. 11 and 12, is provided with a yoke 51 into which the upper end of the spindle projects, such upper end being provided with a thrust bearing 52 in two parts with interposed balls, as shown. Pressure is applied to hold the spindle down by means of the coil spring 53 which bears at its upper end against a plate 54, which is in turn adjusted in position by means of the screw 55. Means are provided for raising the spindle so as to lift the glass carried thereby above the surface of the tables in the form of the lever 56 pivoted to the yoke 51 at 57 and provided with the arm 58 having at its ends suitable anti-friction rollers engaging the lower side of the thrust bearing 52. The lower plate of the thrust bearing is secured to the spindle against longitudinal movement thereon by any suitable means, so that the upward movement of the lever 56 lifts the spindle and the vacuum devices carried at the lower end thereof. The extreme upper end of the lever 56 carries a roller 59, and lifting cams 60 are provided along the path of travel of the spindles

where necessary in order to secure the lifting of such spindles. There is one of these lifting cams in position to engage the rollers 59 and lift the spindles just before the table A is reached so that the sheets carried by the spindles are above the surface of the table as they pass onto such table. This cam terminates at the station marked *a* in Fig. 5, permitting the spindles to lower at this point so that the sheets engage the surface of the table. The next lifting cam is located with its forward end at the station *e* of Fig. 5, at which point the spindles and the sheets carried thereby are lifted from the table and maintained in lifted position until they arrive at a point over the next grinding table B at a point which corresponds to station *a* of the first grinding table A. These lifting cams are located at all points in the system where it becomes necessary to lift the plates of glass to avoid interference or injury in moving the sheets from one table to the next. When it is desired to hold one of the spindles continuously in its upper position, as in case of the breaking of the sheet carried thereby, this is accomplished by manually moving the lever 56 farther to the right than the movement given by the cams, at which time the dog 59^a engages the notch 59^b. This holds the spindle in raised position till the dog is released.

In order to connect the spindles together, the bars 61 are employed, such bars being secured to the spindle casings 27 by means of the vertical pins 31 which carry the rollers 32. The spindle casings taken in conjunction with the bars 61 constitute an endless chain, the spindle casings acting as the pintles in the chain. As indicated in connection with Figs. 1 and 2, the endless chain thus formed passes around the sprockets O, P, Q and R which sprockets, aside from the matter of their location, are substantially the same throughout and are shown in detail in Fig. 11. These sprockets each consist of two spiders 63 and 64 spaced apart and keyed to vertical shafts 65. The ends of the spider arms are recessed so as to engage and fit around the portions 66 and 67 of the spindle casings 27, as indicated in Fig. 11. The eight sprockets P, shown in Fig. 1, are all driven from the line shaft 68 driven from the electric motor S by means of the belt 69 (Fig. 4) passing around the pulley 70 (Figs. 1 and 2) on the line shaft. Opposite each pair of sprockets the shaft is provided with a worm driving a worm wheel 72 upon a transverse shaft 73 (Fig. 2). This shaft is provided with the bevel pinions 74 engaging the bevel gears 75 on short vertical shafts 76 (Fig. 3). These shafts 76 are provided at their lower ends with spur pinions 77 engaging spur gears 78 (Fig. 3) which are keyed to the upper ends of the shafts 65 on

which the sprockets 63 and 64 (Fig. 11) are carried. The other sprockets O, Q and R are all idlers.

Figs. 7 and 8 illustrate the means for applying glass to the suction frames carried by the various spindles 25 preliminary to the grinding operation on table A. In starting the operation, the sheets are placed upon the left-hand end of the conveyor K, as shown in Fig. 1. This conveyor comprises an endless belt passing around the sprockets 80 and 81 and supported against downward movement of its upper flight by the angle iron tracks 82 (Fig. 7) which project beneath the chains comprising the endless carrier and engage the rollers 83 located at the ends of the chain joints. Intermediate the chain joints and extending from the chain on one side to the chain on the other are flat sheet metal plates which together form the continuous flat table K for supporting the sheets during the application of the suction frames. As indicated in Fig. 7, the track which carries the spindles and suction frames extends longitudinally over the endless carrier so that, as the plates of glass which are applied to the table M move along such table, the spindles with their suction frames are carried along at the same rate of speed upon the overhead track. At this time and before the application of pressure means to the vacuum frames to cause the engagement of the suckers with the glass, the spindles are maintained in elevated position by reason of the cam 85 which acts in the same manner as the cam heretofore described in connection with Figs. 11 and 12. The cam 85 is inclined upwardly as indicated at 86 (Fig. 8) to release the spindle holding levers, so that at this point the vacuum devices are to engage the glass plates on the table. The vacuum frames are then carried along beneath the endless belts L located on each side of the center line of the track as indicated in Fig. 7 in position to engage the upper ends of the members 44, which as indicated in Fig. 10, are normally held in their uppermost positions by the springs 45. The pressing down of these members lowers the plates 41 and forces the air out of the chambers 50. At the same time, the plate 42 is pressed down tightly into engagement with the top surface of the glass. This engagement is maintained by the endless belts L until the vacuum frames pass from beneath such belts. The movement from between these belts releases the members 44 of the sucker devices and under the influence of the relatively strong coil springs, the members 44 are raised, thus lifting the plates 41 and enlarging the capacity of the chambers 50, thus producing a suction effect which maintains the sheets of glass tightly against the suckers, as described in my Patent No. 1,294,103.

After the plates have been ground and polished and have passed the last polishing table H, they are released upon an endless carrier M and by means of a pair of endless belts designated by the reference letter N in Fig. 1 which belts as well as the carrier M correspond, except in the particular hereinafter set forth, to the similar devices for applying the plates as above described. The difference above referred to will be seen by reference to Figs. 8^a and 7 which show in side elevation and section, respectively, the release mechanism N. By reference to these figures, it will be noted that along the upper edge of the angle irons 88, which constitute the supporting track for the rollers on the endless carrier, are placed a series of rollers 89 which rollers are positioned so that they lie beneath and engage the outer edges of the suction frames 26. Above the endless carrier M is located the release device N, in the form of a pair of endless belts N, corresponding in location and function to the endless belts L, above described for applying the suction devices. As the vacuum frames pass beneath belts N, such belts engage the members 44 pressing such members down, so that the volume of the chambers 50 is reduced (Fig. 10), thus releasing the suction effect upon the plates of glass, and upon a slightly further movement, the rubber tipped ends 46 of the members 44 engage the glass sheets and push them away from the sucker devices. This release action is made possible by the fact that the edges of the vacuum frame are at this time securely supported against downward movement by means of the rollers 89. In this way, the plates are released from the vacuum frames and dropped upon the endless carrier M from which they are removed by an operator standing to the left of the release device N (Fig. 1). As the spindles and vacuum frames pass the left-hand end of the release device N, their raising levers are engaged by the inclined end of the lifting cam 85 which corresponds in position to the end 86 of the lifting cam 85, shown in Fig. 8, this lifting cam 85 being in the form of a semi-circle which follows the curve of the track carrying the spindles and has one end arranged to engage and operate the levers to lift the spindles, which position is maintained by the cam 85 until the incline 86 is reached. This incline permits the spindles to lower as heretofore described.

The endless carriers M and K are driven from the vertical shafts 91 and 92 (Figs. 1 and 7) which in turn are driven by the sprocket chain 93 passing around the three sprockets 94, 95, and 96 located at the upper ends of the shafts 65, 91 and 92 (Fig. 8) respectively. The sets of bevel gears 97 and 98 on the shaft 91 drive the endless belts M

and outer belt N, while on the other side of the machine a similar driving arrangement from the shaft 92 is provided for the endless belt K and the outer belt L. The inner belts 5 N and L are driven from a pair of other vertical shafts 99 and 100, Figs. 1 and 7, which shafts are provided at their upper ends with sprockets 101 and 102 around which the sprocket chain 93 extends. As 10 indicated in Fig. 7, the inner belts L and N are driven from the shafts 100 and 99, respectively, by means of the sets of bevel gears 103 and 104.

The sprocket Q made up of the spiders 63 15 and 64 mounted on the shaft 65 serves as an adjustment member for taking up the slack in the endless chain or carrier made up of the vacuum frame spindles and interposed links. This sprocket is mounted for longitudinal 20 adjustment in that its lower end is supported in a movable thrust bearing 105 (Fig. 8) and the shaft 65 above this point is carried in a framework made up of the channels 106 which are adjustable longitudinally 25 from the post 107. This post preferably constitutes a portion of the structure in which the grinding apparatus is installed. The thrust bearing 105 lies over a pair of T slots 108 which receive the bolts 109 30 adapted to hold the bearing in any adjusted position. The supporting framework for the shaft 65, made up of the channels 106, is made adjustable with respect to the post 107 by means of the pair of screws 110 which 35 extend through the blocks 111 carried by the channels and engage at their inner ends against the sides of the post 107. The channels 106 are also supported upon the posts 112, also forming a part of the building 40 structure in which the apparatus is installed, such posts being provided with the transverse angles 113 engaging the under sides of the channels 106 and affording an additional support for such channels. After the framework 45 106 is positioned by means of the screws 110, it is secured in adjusted position by suitable bolts or clamps (not shown). The endless track which carries the vacuum frame spindles must also be made adjustable 50 as to length to correspond to the adjustment of the frame 106 carrying the sprocket Q, and this is accomplished in any desired way, as by having the track cut and overlapping, and provided with suitable slots and securing bolts, an expedient well known in mechanics 55 and requiring no illustration.

The preferred construction of the polishing tables is shown in Figs. 21 and 23. These tables are of annular form being cut out at 60 the center 114, and made up of a frame portion 115, which is of any approved form, upon which is mounted a series of perforated steel plates 116 carrying rubber plates 117. Upon the top of the rubber plates are 65 cemented a series of felt sheets 118 which

constitutes the polishing surface of the table. The perforated metal plates 116 are secured in position to the frame by means of the bolts 119. This plate is provided with a plurality of perforations 120 of the form 70 indicated in Fig. 23, the perforations being enlarged at their lower ends. The rubber sheet or plate 117 is vulcanized on the perforated plate 116 and the rubber fills the perforations 120 and a very secure attachment 75 of the rubber plate to the steel plate is afforded, the perforations 120 being sufficiently numerous to give proper holding strength between the two plates. The steel plates 116 are preferably of the shape indicated in Fig. 80 21 with the adjacent side abutting so that a continuous surface is provided.

The operation of the apparatus is as follows: The plates are applied by an operator successively to the endless carrier K and by this carrier they are fed beneath the securing belts L, the feed of the plates being so timed with the endless carrier supporting the vacuum devices that a sheet is positioned beneath each of such devices as the plates and 90 vacuum devices pass between the two sets of endless belts. The pressure of the endless belts upon the upper sides of the vacuum devices causes the attachment of these devices to the plates so that when the plates 95 pass the endless belts L, they are securely supported upon the lower ends of the vacuum frame spindles. As the spindles approach the first grinding table A, their lifting levers come into contact with one of the lifting cams, such as the cam 60 of Fig. 12. The spindles are thus raised so that when the plates pass over the edge of the grinding table, they are elevated above such table and not in danger of injury by contact 100 therewith. The further movement of the spindles on the endless carrier brings them to the station a (Fig. 5), at which point the holding cam for the spindle levers is bent 105 upwards so that the spindles are allowed to descend causing the glass to engage the surface of the grinding table. Here sand is supplied to the table through the pipe 9, such sand being the coarsest from the grader U. The plates are from this point conducted 110 around the table in the path indicated in Fig. 5, a progressive outward movement being given as the plates move circumferentially, so that when the station e is reached, the plate has passed completely across the 115 grinding portion of the table. During this movement successively finer grades have been placed upon the table from the pipes 10, 11 and 12, so that at the station d, a relatively fine grade of sand is employed and 120 the surface of the plate is ground to a considerable degree. At station e, the spindles are again lifted by means of the overhead lifting cam, and they are maintained in this lifted position until they reach the table B 125

at a point corresponding in location to the station *a* of Fig. 5, at which point the plates are lowered and the grinding operation resumed. During the travel from the table A to the table B, it is desirable to wash off any of the abrasive which may be adhering to the plate, and for this purpose suitable washing devices are provided for supplying a stream of water to clean the plates as they pass. It may also be desirable in this intermediate position to tighten up the suckers upon the glass and this may be accomplished, if desired, at this point by the use of other endless belts corresponding to the belts K and L.

After the plates are applied to the grinding table B, the procedure is the same as heretofore described in connection with the table A except that finer grades of abrasive are employed upon this table. The procedure is also similar to that heretofore described, as the plates pass from the table B to the table C and over such table and from the table C to the table D and over that table. The mixture of sand and water from all three tables A, B and C is returned to the common sump V (Fig. 2) of the grader U and each table is supplied with its proper series of grades from such grader, ranging from the coarsest on table A to the finest on table C. Preferably the grinding with sand as an abrasive will be completed upon the table C and emery used for giving the final smooth upon the table D. The emery is preferably applied upon the same principle as used in connection with the application of the sand, that is the coarsest grade applied first, followed by successively finer grades as the plates progress around the circumference of the table.

After the plates pass off of the last table D, they are thoroughly washed off before passing upon the polishing table E. The path of the plates upon this table corresponds to the one heretofore described in connection with the grinding table A, the plates being carried circumferentially of the tables and also laterally so as to distribute the polishing wear over the entire surface of the table. The polishing is preferably accomplished by means of rouge applied with water in the usual way. The plates pass on the endless carrier successively from one table to the other, the polishing being completed upon the last table H. After passing from the table H, the vacuum frames with their plates are carried between the endless belts N and M, and, at this point, the release of the plates is effected, so that they drop down upon the endless belt M, and are removed by an operator stationed at this point. The release by the endless belt M is accomplished by the pressure of the belts N upon the members 44 carried by the upper vacuum plates, which pressure releases

the suction upon the plates, after which the lower ends of the members 44 engage the sheets of glass themselves and push them away from the suckers. At this time the edges of the vacuum frame are supported upon the rollers 89, so that such frames are securely held against downward movement, thus making the pressure of the belts N effective to release the suckers.

A wide variety of grinding tables might be employed other than the one illustrated in Figs. 5, 6, 19 and 20. One such form is illustrated in Figs. 15 to 18. In this form of construction, it is designed that the runner bars should be held removably in position on the table by means of sulphur or some such composition which hardens at a temperature such that it will serve to hold the bars in position until the temperature of the composition is raised in order to release the bars, this being frequently required in glass grinding tables in order to replace the bars worn away by the grinding operation. Referring to Figs. 15 and 16, it will be noted that the framework 121 of the table has bolted to its upper side a plurality of chambers 122 adapted to be supplied with steam through the pipes 123 for the purpose of melting the sulphur bath 124 in which the runner bars 125 are set. These runners may be made in a variety of ways. As illustrated, they consist of a base portion 126 provided with the upstanding diamond shaped blocks 127. The spaces between the diamonds are filled with plaster-of-Paris to reduce the space for the lodgment of abrasive which would enter the spaces almost immediately and be lost from service, thus reducing the grinding speed until the spaces were filled. In order to seat the runner bars at the proper level in the molten bath, the bearing pins 128 are employed, such bearing pins being of the form indicated in Fig. 16 and having their lower reduced ends fixed in recesses 129 in the top walls of the chambers 122, and having their upper ends fitting into recesses in the bottoms of the runner bars, such ends being carefully machined to a common level so that the level of the runner bars is definitely and accurately fixed.

After steam is applied to the chambers 122 and the sulphur melted, the runner bars are positioned and the sulphur allowed to harden. When it becomes necessary to replace the runner bars, the sulphur is melted and the substitution readily made.

Still another form of grinding table is illustrated in Figs. 24 to 27 in which grinding stones of emery, carborundum composition, or some other composition suitable for the purpose are employed in place of the metal grinding bars heretofore described. With a construction of this kind, the grinding may be accomplished without the use of abrasive, such as sand and emery, which is

required in connection with metal grinding surfaces, as heretofore described. With a grinding surface, such as that illustrated in Figs. 24 to 27, water is ordinarily used in order to facilitate the grinding operation and in some cases, this may be applied under pressure against the surface of the stones in order to wash the surface and reduce the tendency of such surface to glaze over. In some instances, it may be found desirable to grind with the sand as an abrasive, as heretofore described, and use the grinding stones only for improving the smooth to the glass after the rough grinding has been accomplished, but in other cases, it may be desirable to do both the rough grinding and the smoothing with the stone or composition grinding surface.

As indicated in the drawings, 130 is the frame or bed of the table, which may be constructed in any desired form, upon which the stones are secured by means of the bolts 131. These stones are preferably made of the size and shape indicated at 132 in Figs. 25, 26 and 27. The stones fit against and support each other at their side edges and are held securely in position by means of the bolts whose heads lie in the countersunk openings 133.

Fig. 14 illustrates a modified form of vacuum frame spindle construction in which the spring 53^a, corresponding in function to the spring 53 of Fig. 12, is mounted inside the spindle casing 27^a. The spring in this instance bears against the thrust bearing 52^a, the lower member of which engages a shoulder upon the spindle 25^a and normally holds such spindle yieldingly in its lowest position. The track which carries this device and the arrangement of rollers for engaging the track is identical with that of the construction of Fig. 11 to 13, being similarly numbered with reference numerals and requiring no further description. The spindle is raised by means of the lever 134 pivoted at 125 upon the bracket 136. The inner forked end of this lever is provided with a pair of rollers 137 adapted to engage the lower plate of the ball thrust bearing 138, the upper plate of such bearing being held in position by means of the collar 139 pinned to the upper end of the spindle 25^a. The outer end of the lever 134 carries the roller 140 adapted to engage the cam 60 and is also provided with a handle 141. When the roller 140 engages the cam 60, the inner end of the lever is raised lifting the spindle against the tension of the spring 53^a and when the roller moves off of the cam at its other end, the spring moves the spindle and the vacuum frame and glass plate carried thereby downward. The lever 134 is provided with a downwardly projecting arm 142 and when the lever is thrown downward to a position below that to which it is

normally moved by the cam 60, the end of this arm 142 is engaged by the gravity operated dog 143. In this way the spindle is held in raised position as long as may be desired. The purpose of this holding arrangement is to get the vacuum frame out of the way in case of an accident, such as the breaking of the glass, carried by the spindle. This dog 143 is released by moving its outer end upward, thus permitting the lever 134 to resume its normal position as secured by the action of the spring 53^a.

The grinding tables, which are mounted on tracks for transfer purposes as heretofore explained, are preliminarily ground by placing them beneath the runners of the ordinary plate glass machine and rotating them, applying abrasive and water until the grinding surface is faced off and trued up. These tables are preferably made similar and interchangeable so that they may be shifted progressively at intervals from the position A to the position D, a new table being placed at A when a shift is made. In this way the grinding faces are partially worn down and smoothed before being used with the finer abrasives and the roughest faces are employed where the more rapid grinding is desired and the roughness will not injure the surface of the glass.

It will be understood that the invention is not limited to the particular embodiments of the plate carrying means, grinding tables and polishing tables, illustrated and described. Other means than the vacuum holding means might be employed, such as embedding the plates in paraffin or other material readily melted to release the plates, although the vacuum device is the preferred means because of the ease of attaching and detaching the plates. The path of the plates over the tables might also be varied within a wide range, the only requirement being that the plates be carried over the tables in such way as to distribute the grinding wear, and the method of securing this result to the best advantage will be dependent upon the conditions to be met. The polishing tables are described as covered with felt, but it will be understood that other polishing surfaces might be employed, such for instance as pitch, which is cheaper than felt and which lends itself to the present apparatus since the polishing surface faces upward instead of downward as is the case in the ordinary machine. Under this condition the pitch holds the polishing material much better than it would if the pitch faced downwardly. The pitch is also easily applied and given a plane surface by heating it and allowing it to find its own level on the table. A wood polishing table might also be used with pumice or other smoothing or polishing powder, and means might be interposed in the path of travel of the

plates after the grinding operation, other than the tables, such as brushes or the like for giving a partial polishing action preliminary to the regular polishing with rouge.

What I claim is:—

1. The combination with a circular driven surfacing table, of means for supporting thereabove a series of sheets of material to be surfaced, and carrier means for giving such means a movement of translation to the table, then circumferentially thereof and finally away from the table.
2. In combination in a machine for surfacing glass plates or sheets, a table mounted for rotation, means for rotating the table, surfacing means upon the upper side of the table, a series of sheet supporting devices each adapted to support a sheet of material to be surfaced with one of its surfaces in opposition to said upper side of the table, and carrier means for said supporting devices to the table from a position remote therefrom, then adapted to move the devices circumferentially of the table, and then away from the table.
3. In combination in a machine for surfacing glass plates or sheets, a table mounted for rotation, means for rotating the table, surfacing means upon the upper side of the table, a series of sheet supporting devices each adapted to support a sheet of material to be surfaced with one of its surfaces in opposition to said upper side of the table, and carrier means for said supporting devices adapted to move the devices to the table from a position remote therefrom, then circumferentially of the table and also radially during the circumferential movement, and then away from the table.
4. In combination in a machine for surfacing glass plates or sheets, a table mounted for rotation, means for rotating the table, surfacing means upon the upper side of the table, a series of sheet supporting devices each adapted to support a sheet of material to be surfaced with one of its surfaces in opposition to said upper side of the table, and endless carrier means for said supporting devices adapted to move the devices to the table from a position remote therefrom, then circumferentially of the table, and then away from the table, the said supporting devices each being supported free to rotate about a vertical axis.
5. In combination in a machine for surfacing glass plates or sheets, a table mounted for rotation, means for rotating the table, surfacing means upon the upper side of the table, a series of sheet supporting devices each adapted to support a sheet of material to be surfaced with one of its surfaces in opposition to said upper side of the table, carrier means for said supporting devices
- adapted to move the devices circumferentially of the table, and means for supplying abrasive, which is progressively finer, to the successive portions of the table over which the sheets are carried.
6. In combination in a machine for surfacing glass plates or sheets, a table mounted for rotation, means for rotating the table, surfacing means upon the upper side of the table, a series of sheet supporting devices each adapted to support a sheet of material to be surfaced with one of its surfaces in opposition to said upper side of the table, carrier means for said supporting devices arranged to move the devices circumferentially around the table and also radially from the inner to the outer side thereof during such circumferential movement, and means for supplying abrasive in progressively finer grades to the successive portions of the table over which the sheets are carried.
7. The combination with a driven surfacing table, of means for carrying a sheet of material to be surfaced over the table comprising a device for engaging and gripping the upper surface of the sheet, means for supporting the device from above free to rotate about a vertical axis, means for giving the device a movement of translation to and from the table and over the table, and automatic means for causing the engagement of the device with the sheet during the movement of the device to the table.
8. The combination with a driven surfacing table, of means for carrying a sheet of material to be surfaced over the table comprising a suction device for engaging the upper surface of the sheet, means for supporting the device from above free to rotate about a vertical axis, means for giving the device a movement of translation to and from the table and over the table, and automatic means for causing the disengagement of the device from the sheet during the movement of the device away from the table.
9. The combination with a series of rotary driven surfacing tables, of means for supporting a series of sheets of material from above, and an endless carrier for giving such means a movement of translation to carry them over the series of tables.
10. The combination with a series of rotary driven surfacing tables, of means for supporting a series of sheets of material from above, a carrier for giving such means a movement of translation to carry them over the series of tables circumferentially thereof, and means for supplying successively finer grades of abrasive to the tables.
11. The combination with a series of rotary driven, grinding and polishing tables, of means for supporting a series of sheets of material from above, and a carrier for

giving such means a movement of translation to carry them over the series of tables and circumferentially of said tables.

12. The combination with a series of driven surfacing tables, of means for supporting a series of sheets of material from above, means for giving such means a movement of translation to carry them over the series of tables, and means for elevating the supporting means after the plates pass off of each table and for lowering such supporting means after the plates arrive over the next table.

13. The combination with a driven surfacing table, of means for carrying a sheet of material to be surfaced over the table comprising a suction device for engaging the upper surface of the sheet, means for giving the device a movement of translation to and from the table and over the table, and a pair of endless belts between which the suction device with the sheet therebeneath is passed on its way to the table and which serve to press the suction device against the plate to cause the engagement therewith.

14. The combination with a driven surfacing table, of means for carrying a sheet of material to be surfaced over the table comprising a suction device for engaging the upper surface of the sheet, means for giving

the device a movement of translation to and from the table and over the table, and a pair of endless belts between which the suction device with the sheet thereon is passed on its way from the table after the surfacing operation, the upper of which belts serves to press downward on the suction device and release it.

15. The combination with a series of driven surfacing tables, of means for supporting a series of sheets of material from above, means for giving such means a movement of translation to carry them over the series of tables, means for elevating the supporting means after the plates pass off of each table and for lowering such supporting means after the plates arrive over the next table, a pair of endless belts between which the suction device with the sheet thereon is passed on its way from the table, the upper of which belts serves to press downward on the suction device to release it, and means for supporting the vacuum device from beneath during the application of said downward pressure on such device.

In testimony whereof, I have hereunto subscribed my name this 25th day of May, 1922.

HALBERT K. HITCHCOCK.
